UNITED STATES PATENT OFFICE.

AUGUST P. LAUSTER, OF BROOKLYN, NEW YORK, ASSIGNEE, BY MESNE ASSIGNMENTS,
TO JOSEPH F. O'BRIEN, OF WEST NEW YORK, NEW JERSEY.

APPARATUS FOR PLAYING GAMES.

1,117,959.

Specification of Letters Patent.

Patented Nov. 17, 1914.

Application filed April 12, 1912. Serial No. 690,223.

To all whom it may concern:

Be it known that I, AUGUST P. LAUSTER, a citizen of the United States, and a resident of Brooklyn, in the county of Kings and State of New York, have invented certain new and useful Improvements in Apparatus for Playing Games, of which the following is a specification.

This invention relates to improvements 10 in apparatus for playing games.

By the use of my invention, I provide in combination with one or more balls or other similar devices means for testing the player's skill in rolling or throwing the ball, such as a long rectangular table suitably supported and having a goal, such as an aperture at its rear end, a prize displayed at a distance from the player and means actuated by engagement with the ball or 20 other suitable device for delivering the prize to the player.

My preferred form of apparatus comprises in combination with a wooden ball or sphere of suitable size, an oblong table 25 having a circular aperture somewhat larger in diameter than the diameter of the ball located near the rear end of the table, a track inclined upwardly from the front end to the rear end of the table, a carriage mounted on the track at its upper or rear end, a prize displayed in the carriage, means 30 on the track for retaining the carriage in position thereon comprising a spring latch and an abutment on the carriage for operating with the latch, and a member 35 hinged to a suitable fixed support, extending below the aperture so as to be engaged and depressed by a ball falling therethrough and a connecting rod connecting the hinged 40 member and the spring latch to withdraw the same when the hinged member is depressed by the ball and permit the carriage and prize to roll down the inclined track to the front of the table within reach of the 45 player.

In the accompanying drawings, in which similar reference characters designate corresponding parts throughout the several views, Figure 1 is a side elevation, partially 50 in section, of apparatus embodying the preferred form of my invention; Fig. 2 is a plan view of the apparatus shown in Fig. 1; Fig. 3 is an enlarged section on the line 3-3 of Fig. 1; and Fig. 4 is an enlarged 55 fragmentary plan view of the upper por-

tion of the inclined track with the carriage removed, showing the latching member and detachable connections.

Referring now to the accompanying drawings, and to the preferred embodiment 60 of my invention shown therein, A designates a table preferably supported in position by detachable legs a a reinforced by detachable connecting strips a', and having 65 detachable marginal side strips a² a², and detachable marginal end strips a³ a³ extending slightly above the surface of the table so as to form on the surface of the table a 70 rolling alley or track for a ball B. The table A is provided near its rear end with a circular aperture A' somewhat larger in diameter than the diameter of the ball B, and supported beneath the aperture A' in 75 position to be engaged by a ball falling therethrough is a member F which, as shown, is hinged at one end to any suitable support such as the depending block A² and is connected intermediate its ends by a rod E to a spring latch D. As illustrated, the latch D, comprising as shown a flat strip 80 of resilient metal, is connected at one end by tacks d d to a track H inclined rearwardly and extending from the front to the rear end of the table and being detachably supported thereon, its rear end being held 85 in elevated relation to the table by a frame A³ also detachably connected to the table, to which frame A³ the track H is connected at one end by hooks h h, secured to an end strip a' its other end being retained in position on the table by a dowel h'. The rod E is preferably connected to the spring latch 90 as follows: The spring end of the latch member D is provided with holes d' d' and the upper end of the rod E is hooked and 95 spans the bridge between these holes.

A carriage G having a prize J displayed thereon, is provided with an abutment g beneath its body which engages the free end of the spring latch member D and the carriage is thus retained in position at the upper end of the inclined track H.

Suitable means such as the run-way K are 105 preferably provided to permit the ball or balls, when the same fall through the aperture A', to run forwardly toward the front of the table.

The operation of the device is as follows: When a player is sufficiently skilful to roll 110 a ball along the table A into the aperture

A' at its rear end, it will fall upon the pivoted spring latch controlling member F which will actuate the rod E to pull down the spring catch D out of engagement with the abutment g on the carriage G, thus permitting the carriage and prize, such as a box of candy, to roll by gravity toward the front end of the table and into proximity with the player.

- 10 Having described my invention I claim.
1. A game apparatus embodying a table provided with an aperture, a car, means for detaining it, means operable by the passage of a movable object through the aperture of the table for releasing said car, and means for imparting movement to said car when free from the restraint of said detaining means.
  2. In a game playing apparatus, the combination of a table provided with an aperture at the rear end, a track inclined upwardly from the front to the rear of the

table, a carriage mounted on the track at its upper end, and means beneath the aforesaid aperture adapted to be actuated by a movable object for releasing the carriage to permit it to roll to the front of the table.

3. In a game playing apparatus, the combination of a movable object, a table provided with an aperture at the rear end, a track inclined upwardly from the front to the rear of the table, a carriage mounted on the track at its upper end, and means beneath the aforesaid aperture adapted to be actuated by the movable object for releasing the carriage to permit it to roll to the front of the table.

In witness whereof, I have hereunto set my hand to the foregoing specification in the presence of two subscribing witnesses.

AUGUST P. LAUSTER.
